X-RAY TUBE

Montford Morrison, Chicago, Ill., assignor, by
mesne assignments, to Westinghouse Lamp
Company, a corporation of Pennsylvania

Application September 22, 1925
Serial No. 57,836

8 Claims. (Cl. 250—35)

This invention relates to X-ray tubes and more particularly to such tubes adopted for radiographic purposes.

The present invention is an improvement upon 5 my copending applications Serial No. 476,155, filed June 9, 1921, Patent No. 1,685,928 issued October 2, 1928, (Case No. 8867) and Serial No. 684,336, filed January 4, 1924 (Case No. 208), such improvements relating to details of construction 10 tending toward simplification of design and uniformity of operating characteristics and in which the anode and cathode are substantially disposed in separate chambers which provide for the elimination of long discharge paths.

15 It is an object of the present invention to provide an X-ray tube in which the cathode and anode are substantially disposed in separate chambers or compartments.

It is a further object of my invention to provide 20 an X-ray tube in which long discharge paths are substantially eliminated, thus furnishing a tube which may be operated in the presence of a substantial gas pressure without liability of detrimental gas ionization occurring.

25 Further objects of the invention will be apparent as the description is read and from the accompanying drawing in which the single view illustrates a longitudinal section of an X-ray tube embodying my invention.

30 Referring to the drawing the main envelope 2 may be of a shape corresponding to that of the gas-filled lamp type and may consist of any suitable glass, such as a hard glass. The envelope may consist of a bulbous portion 3 having 35 a single neck or arm 4, the latter having a re-entrant tube 5 of glass sealed at 6 thereto.

The reentrant tube 5 may be utilized as a support for the anode 7, the latter consisting of a 40 rod of copper or other good heat conducting material having an insert 8 of thorium or the like or a good ray-emitting substance. The end of the copper rod 7 may be suitably secured by screws 9 or the like to a metallic sleeve 11 which is split so as to frictionally engage the inner surface 45 of the reentrant tube 5. The sleeve may be locked in position by the provision of a bayonet slot 12 which engages a protuberance 13 pressed out of the reentrant tube 5 by heating or the like. A leading-in wire 14 may be secured at one end 50 to the copper rod 7 and at its other end may be sealed to a screw base 15 in a manner customarily employed in standard lamp practice. An intermediate portion 16 of the leading-in wire may be sealed in the press 17 of a supplementary re-entrant tube 18, which latter may be fused to an

extension 19 of the neck 4. The device may be suitably exhausted by connection to the extension 19 as at 21.

The main or bulbous portion 3 of the envelope may be divided into separate compartments 22 and 23 by means of a glass or other suitable insulating partition 24 which may be fused at 25 to the envelope and to which may also be secured an insulating sleeve or housing 26. The housing 26 has an opening 27 at one end of such size that 60 the anode may be conveniently slipped therethrough, a smaller opening 28 being provided for exhausting the space within the housing and the compartment 23. The other end of the insulating sleeve 26 is curved at 29 so as to have a radii of 65 curvature corresponding to that of the end 31 of the anode, it being noted that this end of the anode is rounded so as to avoid electrostatic stresses being concentrated, thus eliminating the tendency of overheating at localized points. 70

An opening 32 may be provided in the end 29 of the insulating housing 26 and in this opening a thermionic cathode 33 may be and preferably is disposed. The cathode 33 may consist of one or more turns of wire such as tantalum, 80 the arrangement with respect to the target 3 being such that electrons from the cathode striking the target will produce X-rays which in turn pass along the longitudinal axis of the envelope, through the open space between the turns of 85 the cathode and thence through the end of the envelope to secure a useful purpose. The cathode is closely spaced from the target, the spacing being such that no detrimental ionization takes place of the residual gas within the envelope. That is to say, the mean free path of 90 the molecules of residual gas is greater than the space between the anode and cathode so that the liability of electrons striking gas molecules on their way to the anode is reduced to a 95 minimum.

Current for the cathode may be supplied by leads 34 and 35 which in turn are sealed at 36 and 37, respectively, in the glass envelope. Suitable contact caps 38 and 39 secured to the 100 ends of the leads 34 and 35, respectively, may be provided to furnish connections for attaching to a suitable source of supply.

A metallic shield 41 may be secured by screws 42 to the end 29 of the insulating housing 26, 105 the shield being of such size and material as to effectively screen out undesirable X-radiations.

The device may be evacuated through a suitable connection made at the point 21, the gas pressure under which the tube operates being of 110

the order of that of the gas-filled X-ray tubes, say about 1 micron. If desired, a suitable inert gas such as neon, helium, mercury and the like may be employed, the pressure employed being 5 of the order of that specified.

The present invention is simplified by the separate compartments 22 and 23 in which the anode and the cathode, respectively, are housed. By reason of such construction, long discharge paths 10 extending from the cathode to the lower part of the anode shank 7 are effectively broken by the barrier 24. It is understood, of course, that the space between the insulating housing 26 and the anode shank is so small that ionization therein is 15 effectively prevented; also that the surface of the inner wall of the insulating housing is so great that no appreciable current leakage takes place thereover.

In addition to the foregoing functions of the 20 insulating housing 26, this member also serves to focus the electron stream emanating from the cathode 33 upon the focal spot 8, whereby a sharp focus may be obtained. This results from the accumulation of electrons upon the curved 25 surface 43 of the insulating housing 26 which have a repelling or concentrating action upon the electrons coming from the cathode.

Obviously, modifications may occur to those 30 skilled in the art, but it is to be appreciated that such modifications as come within the scope of the invention as defined in the appended claims are considered by me as falling within the spirit of my invention.

What is claimed is:

35 1. An X-ray tube comprising an envelope, a partition within said envelope for dividing the space therein into two compartments, an insulating sleeve supported by said partition, a portion of said sleeve extending into one compartment and another portion into the other compartment, an anode supported at one end by said envelope and having its other end extending into one end of said sleeve, a cathode mounted in the other end of said sleeve and spaced closely 40 from said anode, and means partially surrounding the end of said sleeve which envelops said cathode for screening out undesirable X-rays.

50 2. An X-ray tube comprising an envelope, a barrier dividing said envelope into an anode and a cathode compartment, an anode supported within said anode compartment, an insulating sleeve carried by said barrier and surrounding a portion of said anode, said sleeve being closely spaced from said anode, a cathode disposed in 55 said cathode compartment and supported by said sleeve, said cathode being closely spaced from said anode, and an inert gas within said envelope.

60 3. An X-ray tube comprising an envelope having a bulbous portion and a neck, a reentrant tube within said neck, an anode supported by said tube and having its end projecting into said bulbous portion, an insulating barrier within said bulbous portion for separating the same into two compartments, an insulating sleeve carried by said barrier and surrounding the end of said anode, a cathode mounted in the end of said sleeve and disposed adjacent the end of said anode, said anode and cathode being disposed in axial alignment with the longitudinal 65 axis of said envelope whereby X-rays generated at said anode emerge from said tube along the longitudinal axis thereof.

70 4. An X-ray tube comprising an envelope having a bulbous portion and a neck, an anode sup-

ported by said neck and extending within said bulbous portion, a partition disposed medially of said bulbous portion, an insulating sleeve supported by said partition and closely disposed adjacent the end of said anode, the end of said sleeve being substantially closed but having an opening therein in axial alignment with the longitudinal axis of said envelope, a helical cathode disposed in said opening, the spacing of the end of said anode and said cathode being such that no appreciable gaseous ionization occurs even in the presence of a substantial gas pressure, and means for screening out undesirable X-radiations. 80

5. An X-ray tube comprising an envelope having a bulbous portion and a neck extending therefrom, a reentrant tube within said neck, an anode supported by said tube, the end of said anode extending within said bulbous portion, a partition medially disposed within said bulbous portion, an insulating housing supported by said partition, said housing having its one end substantially closed but having an opening therein for the passage of X-rays, a cathode disposed in the opening, said cathode being formed to pass X-rays without interception, said anode, opening, 90 and cathode being disposed in axial alignment whereby useful X-rays may be generated and emitted from said tube in the direction of its longitudinal axis. 95

6. An X-ray tube comprising an envelope, a 100 partition for separating said envelope into two compartments, an insulating sleeve carried by said partition, a portion of said sleeve extending on each side of said partition, said sleeve being substantially closed at one end but having 110 an opening of small diameter therein, the other end of said sleeve having a larger opening therein, an anode supported by said envelope and having its end projecting through said larger opening to a point adjacent said smaller opening, said 115 anode being closely spaced from the interior wall of said sleeve and having its end rounded, the interior surface of said sleeve adjacent the end having the smaller opening being concave and a cathode disposed in the smaller opening, said 120 tube containing gas at a substantial pressure.

7. An X-ray tube comprising an envelope having a spherical bulb and a tubular extension extending therefrom, a reentrant tube secured to said tubular extension at the anode side of said 125 envelope, an anode supported by said reentrant tube, a partition within said spherical bulb separating the same into two compartments, said partition having a central opening therein through which the end of said anode extends, and a thermionic cathode supported by said partition. 130

8. An X-ray tube comprising an envelope, a reentrant tube secured to the anode side of said envelope, an anode supported at one end of said 135 envelope by said reentrant tube and a cathode supported at the other end of said envelope, a partition intermediate the ends of said envelope and secured thereto, said partition having a tubular portion concentric with the anode and surrounding the end thereof, an opening therethrough to permit electrons to pass from said cathode to said anode, said partition supporting said cathode, the spacing of said anode and cathode being such that said electrons in passing to 145 said anode do not cause appreciable gas ionization.

MONTFORD MORRISON.
